UNITED STATES PATENT OFFICE.

JEFFERSON DAVIS JONES, OF CORSICANA, TEXAS.

TIE-HANDLING APPARATUS

1,186,002.

Specification of Letters Patent.

Patented June 6, 1916.

Application filed February 25, 1916. Serial No. 80,472.

To all whom it may concern:

Be it known that I, JEFFERSON DAVIS JONES, a citizen of the United States, residing at Corsicana, in the county of Navarro and State of Texas, have invented a new and useful Tie-Handling Apparatus, of which the following is a specification.

This invention relates to apparatus especially designed for use in removing old ties and replacing them with new ones, without disturbing the rails resting on the ties.

Another object is to employ mechanism of this type mounted on a hand car or the like which can be brought to position above the ties to be removed, said car carrying mechanism which will operate to pull a tie laterally from beneath the rails and, if desired, at the same time direct a new tie into the space under the rails thus produced.

20 A further object is to employ means for clearing out the space below the rails so that there will be no obstructions interfering with the admission of a new tie to said space.

25 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

35 In the accompanying drawings the preferred form of the invention has been shown.

In said drawings:—Figure 1 is a bottom plan view of the mechanism constituting the present invention, the cranes being 40 shown extended in opposite directions from the body. Fig. 2 is a side elevation, one of the cranes being extended laterally and shown in section while the other crane is extended upwardly and has its upper portion removed. Fig. 3 is a section on line A—B Fig. 1, one of the cranes being shown extended laterally and the other being shown extended upwardly. Fig. 4 is an elevation of a portion of the apparatus and

50 showing the positions of the parts while guiding a new tie into a space already provided therefor. Fig. 5 is a perspective view of the clearing shoe used in connection with a new tie when being moved independently of an old tie, the position of the tie being indicated by dotted lines. Fig. 6 is a plan

view of a portion of a tie having the shoe attached thereto and showing the means provided for connecting the shoe to the tie and for connecting the tie to the handling mechanism. Fig. 7 is a perspective view showing portions of two ties detachably connected. Fig. 8 is a section on line C—D Fig. 7.

Referring to the figures by characters of reference 1 designates a hand car structure adapted to travel along a track to be repaired and secured to the sides of this structure between the supporting wheels 2 are depending side frames 3 connected at their front and rear ends by cross bars 4. Mounted on these cross bars are bearing members 5 in which are journaled the ends of a shaft 6 which is provided, at its center, with opposed clutch members 7 and 8 and a sprocket 75 9, the sprocket receiving motion through a chain 10 from a sprocket 11 driven by a motor 12 on the platform of the car structure. Obviously any other means may be used to drive the shaft 6.

80 Loosely mounted on shaft 6 between clutch member 8 and one end portion of the shaft is a spool or windlass 13 having a clutch member 14 shiftable into and out of engagement with the clutch member 8. Another 85 spool or windlass 16 is loosely mounted on shaft 6 between the clutch member 7 and the other end of said shaft and is likewise provided with a clutch member 17 shiftable into and out of engagement with the clutch member 90 7. Any means desired may be provided for shifting these clutch members 14 and 17. For example, independently operated levers 18 may be pivotally mounted under the car structure, said levers being connected to the 95 respective clutch members 14 and 17 as shown particularly in Fig. 1. Thus by shifting either lever in one direction, the spool connected thereto will be coupled to the shaft 6 whereas when said lever is shifted in the 100 opposite direction the spool will be uncoupled from the shaft.

Pivotally mounted upon one of the side frames 3 is a crane jib 19 mounted to swing upwardly and downwardly and preferably 105 tapering toward its outer or free end. This jib has a brace 20 pivotally connected to its outer end portion and said brace is adapted, when the jib is extended laterally from the car structure, to engage a retaining stud or 110 projection 21 on the platform or deck of the car thus to support the jib in a slightly in-

clined position as shown particularly in Fig. 3. When the jib is in its raised position, as shown at the left of Fig. 3, it will be held in such position by a hook 22 or the like en- 5 gaging the projection 21. Adjustably connected to the outer end portion of the jib is a stem 23 to one end of which is pivotally attached a base plate 24. When the jib is ex- 10 tended laterally beyond the car structure, this base plate is adapted to engage the sur- 15 face of the ground so that the stem 23 co- operating with the brace 20 will prevent the car structure from tilting while in use. An- 20 other crane jib 25 is mounted upon the other side frame 3 and is similarly provided with a brace 20, a hook 22, a stem 23 and a base plate 24. These two jibs are not disposed directly opposite each other but, as shown in Fig. 1, one of them is arranged in advance 25 of the other.

Pivottally connected to each of the frames 3 is a latch bar 26. These bars are arranged directly opposite the jibs and are extended toward the respective jibs. Each bar is 25 adapted to rest upon one of the rails upon which the car is mounted and has a stop lug 27 for engaging the inner side of the rail. Thus when the jib at the right side of the car is extended laterally, the latch bar 26 30 connected to the opposite side of the car will rest upon the right hand rail and prevent the car from pulling toward the right. At the same time the latch bar which is pivotally connected to the right side of the car 35 will engage the left rail and prevent the car from thrusting toward the left. This will be obvious by referring to Fig. 3. The latch bars can be adjustably supported by rods 28 pivotally connected to them and extending 40 through brackets 29 on which the bearings 5 are mounted. By pulling upwardly on the rods and securing them in any suitable manner, the latch bars will be supported out of engagement with the rails. In the drawings, the rails have been indicated at R.

Journaled within the outer end portion of each of the jibs is a double sheave or pulley 30 engaging a cable 31 one end of which is fastened to a pulley block 32. This cable is 50 extended around the pulley 33 and the pulley 30 and is secured at its other end to one of the spools 13 and 16. In other words, the cable 31 carried by one of the jibs is attached to spool 13, while the cable carried 55 by the other jib is attached to spool 16.

Connected to each block 32 in any desired manner, as by means of chains 34 are tongs 35 adapted to embrace and bite into opposed faces of a tie T as shown particularly in 60 Figs. 3 and 6.

Should it be desired to remove an old tie from under the rails and, at the same time, to replace it with a new tie, the car is brought to position above the point where 65 the change is to be made and the latch bars

26 are lowered into engagement with the rails. One of the jibs is then lowered to the position shown in Fig. 3 and the tongs 35 carried by said jib are placed in engagement with one end of the old tie T. A new tie in- 70 dicated at T' is placed with one end against one end of the old tie T and is fastened thereto by means of a coupling staple such as shown at S. After the spikes connecting the tie T to the rails have been removed the 75 spool connected to the cable mounted on the jib in use is coupled to shaft 6 and said shaft actuated so that the cable will be caused to wind upon the spool. Thus the old tie T will gradually be pulled from 80 under the rails and at the same time will pull the new tie T' into position under the rails.

Should it be desired to place a new tie in position at some time subsequent to the removal of an old tie, it is desirable to place 85 the advancing end of the new tie between the upstanding flanges 36 of a clearing shoe 37 the front edge of which is preferably sharpened and shaped to form a lip, as shown at 38. Slots 39 are formed in the 90 flanges 36. The points of the tongs are inserted through the slots and into engagement with the new tie as shown in Fig. 6 so that when said tie is drawn longitudinally, the shoe 37 will be held thereto and will 95 clear the path of the new tie so that it will move to position without encountering any obstruction. By employing the structure described it becomes unnecessary to provide any special means for attaching the shoe to 100 the tie. Instead the tongs employed for coupling the tie to the pulling mechanism also serve as a means for attaching the shoe to the tie. Obviously when the mechanism is not in use, both of the jibs can be held in 105 upstanding position and the latch bars 26 will also be raised so that the car can thus be transported readily from place to place.

It is to be understood that where the tongs are to be used in connection with the shoe 110 37 for the purpose of placing a new tie in position, it is advisable to connect the chains 34 of the tongs to one end of a rod 40 which is of sufficient length to reach under the two rails of the track before the operation of 115 drawing the new tie into position is commenced.

What is claimed is:—

1. Tie handling apparatus including a car structure, a jib connected to one side of said structure and adapted to swing upwardly and downwardly relative thereto, means adjustably connected to and carried by the jib for engaging the ground and supporting the outer end of the jib, supplemental means 120 connecting the outer end portion of the jib to the car structure to support the jib in laterally extended or active position, a block and tackle carried by the jib, tie engaging tongs connected to the block and tackle, and 125 130

power driven means upon the car structure for actuating the block and tackle to pull a tie engaged by the tongs out of position under the car.

- 5 2. Tie handling apparatus including a car structure, a jib connected to one side thereof and adapted to swing upwardly and downwardly, tongs connected to the jib, power actuated means carried by the jib for pulling
- 10 the tongs, and a tie receiving shoe having tong receiving openings therein at the sides

thereof, said tongs constituting means for gripping a tie and for holding the shoe upon the gripped tie.

In testimony that I claim the foregoing as 15 my own, I have hereto affixed my signature in the presence of two witnesses.

JEFFERSON DAVIS JONES.
